CLAIM

The ornamental design for a toothbrush, as shown and described.

DESCRIPTION

FIG. 1 is a front, top and right side perspective view of a first embodiment of the toothbrush;

FIG. 2 is a front elevational view thereof;

FIG. 3 is a right side elevational view thereof;

FIG. 4 is a rear side elevational view thereof;

FIG. 5 is a left side elevational view thereof;

FIG. 6 is a top plan view thereof;

FIG. 7 is a bottom plan view thereof;

FIG. 8 is a front, top and right side perspective view of a second embodiment of the toothbrush;

FIG. 9 is a front elevational view thereof;

FIG. 10 is a right side elevational view thereof;

FIG. 11 is a rear side elevational view thereof;

FIG. 12 is a left side elevational view thereof;

FIG. 13 is a top plan view thereof;

FIG. 14 is a bottom plan view thereof.

FIG. 15 is a front, top and right side perspective view of a third embodiment of the toothbrush;

FIG. 16 is a front elevational view thereof;

FIG. 17 is a right side elevational view thereof;

FIG. 18 is a rear side elevational view thereof;

FIG. 19 is a left side elevational view thereof;

FIG. 20 is a top plan view thereof;
FIG. 21 is a bottom plan view thereof.
FIG. 23 is a front, top and right side perspective view of a fourth embodiment of the toothbrush;
FIG. 24 is a front elevational view thereof;
FIG. 25 is a right side elevational view thereof;
FIG. 26 is a rear side elevational view thereof;
FIG. 27 is a left side elevational view thereof; and,
FIG. 28 is a top plan view thereof.
